UNITED STATES PATENT OFFICE

101,589

DESIGN FOR A COMBINED TRANSFORMER HOUSING AND WALL BRACKET FOR IL- LUMINATED DISPLAY STAND

Richard E. Miesse, Chicago, Ill., assignor to General Scientific Corporation, Chicago, Ill., a corporation of Illinois

Application February 24, 1936, Serial No. 61,311

Term of patent 7 years

To all whom it may concern:

Be it known that I, Richard E. Miesse, a citizen of the United States, residing at Chicago, in the county of Cook and State of Illinois, have invented a new, original, and ornamental Design for a Combined Transformer Housing and Wall Bracket for Illuminated Display Stand, of which the following is a specification, reference being had to the accompanying drawing, forming part thereof.

Fig. 1 is a front view of the wall bracket; and Fig. 2 is a perspective view of the wall bracket.
I claim:

The ornamental design for a combined transformer housing and wall bracket for illuminated display stand as shown.

RICHARD E. MIESSE.
